ABSTRACT

A fully controllable electron tube comprising a plate, a cathode, a first electrode to accelerate an electron beam near the cathode and a second electrode between the first electrode and the plate, used to produce an approximately equipotential space between the first and second electrodes. The tube may be used to rectify and invert voltages in D.C. transmission lines of 1Mv and upward.

HIGH VOLTAGE ELECTRON TUBE

BACKGROUND OF THE INVENTION

1. Field of the Invention

The present invention relates to vacuum tubes, and more specifically, to electron tubes used in electrotechnical and electronic conversion circuits, and may be used at substations of D.C. transmission lines and in high-voltage modulator circuit.

2. Description of the Prior Art

Known in the art are electron tubes comprising a cathode a plate and an electrode placed between them and capable of commutating a voltage of hundreds of kilovolts at hundreds of amperes, wherein electrons are first accelerated to energy close to the rated operating voltage of the tube and then decelerated to a low energy, as a result of which the potential difference between the cathode and the plate, i.e., the voltage drop across the tube, is not great. Thus, for example, at a rectified voltage of 2Mv the potential difference between the cathode and the plate may amount to only a few kilovolts. In the first portion of the tube electrons are accelerated to 1 Mev and in the second portion they are decelerated to several kev.

The length of such a tube should be rated to a double operating voltage since, practically, a full operating voltage is applied to both the accelerating and decelerating sections. In this tube it is necessary to accelerate electrons to the rated (operating) voltage which causes considerable thermal losses due to the accidental bombardment of tube parts by fast electrons, local heating-up, vacuum leakage as well as a considerable amount of radiation. In addition, providing the electric strength of the vacuum gap to which about a million volts is applied while an electron beam of hundreds of amperes passes through the gap, poses an extremely complex physical and technological problem. The solution of this problem is all the more complex, the greater the voltage, the current and the length of the operating pulse.

SUMMARY OF THE INVENTION

It is an object of the present invention to provide a fully controllable electron tube capable of passing heavy currents (hundreds of amperes) at a small voltage across the tube the tube is also capable of withstanding inverse voltages of hundreds and thousands of kilovolts, and has smaller dimensions, a simpler design and less radiation-hazardous. Said object is attained by providing an electron tube comprising a cathode, a plate and an electrode to accelerate the electron beam disposed between the cathode and the plate; the electron tube is supplied, according to the invention, with a second electrode placed between the first electrode and the plate and used to produce an approximately equipotential space in the gap between the first and second electrodes.

It is advisable to set up a lens system in the electron tube between the first and second electrodes to focus the electron beam.

The cathode in the electron tube may be designed in the form of a series of concave-faced rings placed one under the other, the first electrode in the form of a series of rings placed one under the other around the cathode and interspaced by solid annular gaps for the passage of electron beams, the plate in the form of a se-

ries of annular chambers equal in number to cathode rings places one under the other and having solid plate annular slots to receive electron beams, and the second electrode in the form of a series of rings placed one under the other near the plate annular chambers and interspaced by solid annular gaps corresponding to the annular chamber slots, the cross-sections of the annular gaps between the second electrode rings being considerably larger than those of the annular gaps between the first electrode rings to ensure a minimal density of the electron beam near the plate.

It is also possible to design the cathode and the electron tube in the form of a series of plates along the generatrix of a cylinder, the first electrode in the form of a series of rods equal in number to plated placed around the cathode parallel to the plates and interspaced by gaps for the passage of electron beams, the plate in the form of a series of chambers equal in number to the plates set along a circumference larger in radius than the cylinder generatrix, each opposite its cathode plate and provided with slots to receive electron beams, the second electrode in the form of a series of rods equal in number to the chambers placed near the plate chambers and interspaced by gaps to match the chamber slots, the cross-sections of the gaps between the second electrode rods being considerably larger than those of the gaps between the first electrode rods to ensure the minimal density of the electron beam near the plate.

It is desirable to provide the second electrode in the electron tube with some means for setting up a magnetic field in its gaps for protection against the electron beam.

An electron tube, according to the present invention, successfully copes with the above-stated objects and may be used to rectify and invert voltage in D.C. transmission lines of 1 Mv and above.

In this tube the problem of providing the electric strength of the vacuum gap long exposed to about 1 Mv and passing many hundreds of amperes through the electron beam is obviated. Tubes, constructed according to the present invention, will likewise make it possible to increase voltage and average power in the electronic and radio engineering pulse circuits.

BRIEF DESCRIPTION OF THE DRAWING

The invention will be more clearly apparent from the following detailed description of the embodiments thereof with reference to the accompanying drawings, in which:

FIG. 1a illustrates schematically an electron tube according to the invention;

FIG. 1b illustrates the distribution of potentials in this electron tube;

FIG. 2 illustrates an electron tube with a focusing lens system;

FIG. 3a; illustrates an embodiment of the electron tube having ring-type cathodes;

FIG. 3b illustrates the lines of force of the electron tube of FIG. 3a;

FIG. 4 illustrates an embodiment of the electron tube having cathodes in the form of plates.

DESCRIPTION OF PREFERRED INVENTIVE EMBODIMENTS

(FIG. 1a), a plate 2 and an electrode 3; an electrode 4 is placed between the electrodes 3 and the plate 2.

The cathode 1, the plate 2 and both electrodes 3 and 4 are enclosed in a vacuum envelope 5. An approximately equal potential positive relative to that of the cathode 1 is set on the electrodes 3 and 4. Within a space 6 between the electrodes 3 and 4, the electric-field gradient set by these electrodes, is approximately zero. The electron flow accelerates between the cathode 1 and the electrode 3 and then moves by inertia through the space 6 up to the electrode 4. The potential of the plate 2 is maintained approximately equal to that of the cathode 1 and, as a result, there is a decelerating electric field between the electrode 4 and the plate 2 wherein electrons are decelerated imparting their kinetic energy to the electric field. As electrons reach the plate 2, their energy is close to zero and therefore the thermal losses across the plate 2 are small. An approximate potential distribution in the above-described conditions (conduction) is shown by the line 7 in FIG. 1b. The dotted line shows the potential inside the electron beam with due allowance for the space charge of the beam itself.

When a full operating voltage is applied to the tube (the tube is cut off), the potential distribution is approximately uniform (the line 8), which is achieved by usual technical facilities (sectionalization of the vacuum envelope 5, setting a voltage divider along the tube, etc.).

When the tube is conducting the potential difference between the cathode 1 and the electrode 3 is much smaller than the voltage commutated by the tube. For instance, when the operating (commutated) voltage in 1 Mv the potential difference may be between 10 and 50 kv and the maximum electron energy in the tube is likewise between 10 and 50 kev. As electrons reach the plate 2, their energy may be reduced to 0.3-4 kev by deceleration in the section between the electrode 4 and the plate 2.

As the electron beam travels through the equipotential space 6, its own space charge will increase in size and will either be held by focusing lenses in a column of a nearly permanent diameter or provides for sufficiently large inlets in the electrode 4 and the plate 2.

FIG. 2 illustrates an embodiment of the tube wherein a magnetic focusing system 9 is installed between the electrodes 3 and 4. Between the electrodes 3 and 4 the envelope 5 is sectionalized and provided with a number of intermediate plates 10 holding lenses 11 of the magnetic focusing system 9. The lenses 11 may be annular permanent magnets set in an antiparallel fashion as illustrated in FIG. 2.

The existing magnetic materials make it possible to obtain fields of the order of 1,000 gauss with a magnet centre hole of several centimetres in diameter. The use of such magnets makes it possible to convey a beam of about 50 kev at 30-50 amperes in a column 1-2 cm in diameter.

Quadrupole lenses may also be used to improve the focus properties of the system 9.

In this embodiment the electron tube is also provided with an additional electrode 12 placed between the cathode 1 and the electrode 3 and used to facilitate control over the tube current.

The plates 10 receive a potential approximately equal to that of the electrodes 3 and 4. To maintain said potential across the plates 10 they are interconnected and connected to the electrodes 3 and 4 via ohmic resistors 13 outside the envelope 5.

The lower is the level of electrons hitting the elements of the magnetic focusing system 9 the higher may be the resistance of these resistors 13. The same resistors provide a uniform distribution of the inverse voltage across the tube.

The distance between the electrodes 3 and 4 is fully determined by the voltage commutated by the tube and, in general, may reach a few metres. Such dimensions may be required if the tube operates at 1 Mv and 10 the ambient working medium is the ordinary atmosphere. In this case the tube length is determined by the electric strength of the envelope face 5. If the tube is placed in a better insulating medium (oil or compressed gas) it will be determined by the electric 15 strength of the envelope surface 5 facing the vacuum with possible gradients of 1-2 Mv/m.

To reduce the bombardment the elements of the focusing system 9 by electrons, the beam is shaped in the zone of the cathode 1 for which purpose, for instance, a bunched-beam gun may be used. A drop in the inverse current from the plate 2 arising out of a secondary emission, is achieved by shaping its geometry in the form of a deep cavity (chamber) or by other methods. In any event, when electrons hit the plate the energy cannot be zero due to the thermal diversity of electron velocities in the beam, transverse velocities as a result of lens aberrations, etc. This causes the cathode potential to be always somewhat higher than the plate potential. In designing the herein disclosed tube the minimal plate potential and, consequently, minimal losses in the tube are ensured by selecting the geometry of the plate and the electrode 4. The tube current may be increased, among other things, by placing within the same envelope several independent channels each with 20 its own cathode focusing system and plate.

FIG. 3a illustrates an embodiment of the electron tube in which the cathode 1 is designed in the form of a series of rings 14 placed one under the other, the electrode 3 is designed in the form of a series of rings 30 15 equal in number to the cathode rings 14 and concentric relative to them. The rings 15 are affixed to one another with the aid of parts 16, embracing the cathode rings 14 on the inside thus making it possible to interspace the rings 15 by solid annular gaps 17 for the passage of disk-shaped electron beams without losses. Each cathode ring 14 is surrounded by a plate 2 annular chamber 18, set concentrically to the cathode ring and provided with an annular slot 19 to receive the electron beam. The diameter of the annular chamber 18 is considerably larger than that of the ring 14. The electrode 4 is also designed as a series of rings 20, concentric to the annular chambers 18 and somewhat smaller in diameter than the chamber 18. Rings 20 are 35 interspaced by solid annular gaps 21 to match the annular slots 19.

The cross-sections of annular gaps 21 is five to 50 times as large as that of the annular gaps 17. The entire above-described annular construction is enclosed in the vacuum envelope 5, provided with an insulator bushing 22.

The rings 14 of the cathode 1 have a concave emitting (external) surface which enables the size of the electron beam at first to be reduced along the tube axis 23. The electrons accelerated in the section between the cathode 1 and the electrode 3 are then propelled in the approximately equipotential space 6 towards the electrode 4. Meanwhile, the cross-section of the beam

considerably increases and the density falls off accordingly. The low density of the beam in the section between the electrode 4 and the plate 2 (the deceleration zone) facilitates the deceleration of electrons to low energies.

To protect the electrode 4 against undecelerated electrons a magnetic field may be set up in the gaps 21, somewhat reducing the size of the beam in the zone of the electrode 4.

Such a magnetic field may be set up by passing electric current through the rings 20 from a source not shown in FIG. 3a. FIG. 3b illustrates the lines of force 24 of such a magnetic field.

The voltage commutated by the tube, is determined by the electric strength of the gap between the electrodes 3 and 4 and may reach 200-400 kv. At higher voltages it may prove to be difficult to maintain the electric strength of this gap, although there is no electron beam where this high voltage is applied to the gap. The current in the tube may be increased by increasing the number of layers in the annular construction. Allowance should be made for the interaction of electron beams, which affects particularly the trajectory of electrons in the two extreme beams.

FIG. 4 illustrates another embodiment of the electron tube in which the cathode 1 is designed in the form of a series of plates 25 set parallel to the tube axis 23 along a cylinder generatrix, the first electrode 3 is designed in the form of a series of rods 26 parallel to the plates 25 and interspaced by gaps 27 for the passage of electron beams, the plate 2 is designed in the form of a series of chambers 28 equal in number to the plates and set along a circumference larger in radius than the cylinder generatrix, each chamber 28 being set opposite its plate 25 and provided with an annular slot 29 to receive the electron beam.

The second electrode 4 is designed in the form of a series of rods 30 equal in number to the chambers placed near the chambers 28 and interspaced by gaps 31 to match the annular slots 29. It should be noted that the cross-sections of the gaps 31 are 5 to 50 times as large as the cross-sections of the gaps 27 to provide the minimum density of the electron beam near the plate 2.

Electric current may be passed through the rods 30 of the electrode 4 in this embodiment of the tube, to set up a magnetic field, as described above.

The tube in this embodiment operates like the tube illustrated in FIGS. 3a, 3b.

This tube design like the embodiment illustrated in FIGS. 3a, 3b, provides a reduced beam density in the deceleration zone. The range of characteristics in which the tube designs shown in FIGS. 3a, 3b and 4 may operate embraces currents of hundreds and thousands of amperes, the maximum operating voltage of 200-400 kv, a voltage drop across the tube in conduction amounting to tens or hundreds of volts.

The tube designs in FIGS. 3a, 3b and 4 can provide heavier currents and smaller voltage drops as compared to the embodiment in FIG. 2 but are used for lower commutated voltages.

What is claimed is:

1. A high voltage electron tube comprising:
a vacuum envelope;
a plate member disposed in said vacuum envelope;
a cathode member disposed in said envelope;

a first electrode to accelerate an electron beam placed in said vacuum envelope near said cathode member;

a second electrode placed in said vacuum envelope between said first electrode and said plate member at such a distance from said first electrode so as to ensure the electric strength in a gap between said first and second electrode under the conditions when an inverse voltage is applied to the tube, whereas under the conditions when a forward voltage is applied to the tube, the potentials of both said electrodes are close to each other and the potential of said plate member is substantially lower than that of said second electrode and close to that of said cathode member; and

said plate member being a chamber anode and having a surface substantially larger than an orifice in said second electrode for the reception of a decelerated electron beam.

2. A high voltage electron tube as claimed in claim 1, which includes a system of magnetic lenses disposed between said first and second electrodes for focusing the electron beam.

3. A high voltage electron tube comprising:
a vacuum envelope;
a plate member disposed in said vacuum envelope;
a cathode member disposed in said envelope, said cathode member comprising a series of concave-faced rings placed one beside the other;
a first electrode to accelerate an electron beam placed in said vacuum envelope near said cathode member, said first electrode comprising a series of rings placed one beside the other around said cathode member and inter-spaced by uninterrupted annular gaps for the passage of electron beams;

said plate member comprising a series of annular chambers equal in number to said cathode rings placed one beside the other and having uninterrupted annular slots to receive electron beams; and a second electrode placed in said vacuum envelope between said first electrode and said plate member for producing an approximately equipotential space in a gap between said first and second electrodes, said second electrode comprising a series of rings placed one beside the other near annular chambers of said plate member and inter-spaced by the annular gaps corresponding to said annular slots of annular chambers, the cross-sections of said annular gaps between said second electrode rings being substantially larger than those of said annular gaps between said first electrode rings to ensure a minimal density of the electron beam near said plate member.

4. A high voltage electron tube comprising:
a vacuum envelope;
a plate member disposed in said envelope;
a cathode member disposed in said envelope, said cathode member comprising a series of plate members along the generatrix of a cylinder;
a first electrode to accelerate an electron beam placed in said vacuum envelope near said cathode member, said first electrode comprising a series of rods equal in number to said plate members placed around said cathode member parallel to said plate members and inter-spaced by gaps for the passage of electron beams;

said plate member comprising a series of chambers equal in number to said plate members set around a circumference larger in radius than said cylinder generatrix each opposite its said cathode plate member and provided with slots to receive electron beams; and

said second electrode comprising a series of rods equal in number to said chambers placed near said plate chambers and interspaced by gaps to match said chamber slots, the cross-sections of said gaps between said second electrode rods being substantially larger than those of said gaps between said

first electrode rods to ensure a minimal density of the electron beam near said plate member.

5. A high voltage electron tube as claimed in claim 3, wherein said second electrode is provided with a means of setting up a magnetic field in its gaps for protection thereof against the electron beam.

6. A high voltage electron tube as claimed in claim 4, wherein said second electrode is provided with a means of setting up a magnetic field in its gaps for protection thereof against the electron beam.
